W. F. CORSON,
MACHINE FOR PRINTING TUBES,
APPLICATION FILED MAR. 17, 1919.

1,382,171.

Patented June 21, 1921.

Fig. 1.

UNITED STATES PATENT OFFICE.

WILLIAM FREELAND CORSON, OF TORONTO, ONTARIO, CANADA.

MACHINE FOR PRINTING TUBES.

1,382,171.

Specification of Letters Patent. Patented June 21, 1921.

Application filed March 17, 1919. Serial No. 283,058.

To all whom it may concern:

Be it known that I, WILLIAM FREELAND CORSON, a subject of the King of Great Britain, and resident of the city of Toronto, 5 county of York, Province of Ontario, in the Dominion of Canada, have invented certain new and useful Improvements in Machines for Printing Tubes, described in the following specification and illustrated in the accompanying drawings, that form part of the same.

The principal objects of the invention are, to effect a saving of time in the printing of collapsible tubes and to devise a printing 15 machine which will enable the tubes being handled very rapidly and which will print them very accurately.

The principal feature of the invention consists in the novel construction and arrangement of parts, whereby a rotatable mandrel for holding the collapsible tubes is supported upon a carriage adapted to travel upon a frame to bring the tubes into rolling contact with a printing surface, and whereby 20 the tube is carried clear of the printing surface on the return movement and the printing surface is re-inked.

In the drawings, Figure 1 is a plan view of a machine constructed in accordance with 30 my invention.

Fig. 2 is a side elevational view.

The frame 1 of the machine is of rectangular form supported upon legs 2. A carriage 3 is slidably mounted on the top of the 35 frame and is formed of a pair of angle members 4 having the upwardly extending lugs 5 arranged midway of their length. These lugs are connected together by a cross bolt 6.

A frame 7 is pivotally mounted upon the 40 bolt 6 and is provided with a laterally offset lug 8 extending rearwardly from one side of said frame and forming the bearing support for the rotatable mandrel 9.

A handle frame 10 is pivotally supported 45 upon the bolt 6 between the pivotal supports of the frame 7 and a handle 11 is carried at the upward end thereof.

The mandrel 9 extends inwardly from the lug 8 back of the handle 11 and is unsupported at its outer end so that the open ended collapsible tube may be placed 50 thereon.

A toothed rack 12 is secured to the top of the frame at the inner side of one of the 55 angle members 4 of the carriage and a toothed pinion 13 is arranged upon the inner

end of the mandrel to engage the toothed rack.

A spiral spring 14 is arranged to loosely surround the bolt 6 between the bearing lug 60 support of the frame 7 and one end of the spring engages the frame, forcing it downwardly to maintain the pinion in operative engagement with the rack.

A frame 15 similar to the frame 7 is 65 formed with the lugs 16 rotatably encircling the cross bolt 6 and having the outwardly extending arms 17 projecting in a direction opposite to the lug 8 and in a substantially horizontal direction, said arms supporting 70 the inking roller 18.

A pin 19 carrying the inking roller projects beyond the sides of the arms 17 and is adapted to engage the stops to limit the downward movement of the roller. The opposite end of the spiral spring 14 engages the 75 cross bar of the frame 15 to hold the inking roller downwardly.

A pivotal member 20 is secured to one side of the carriage by the cap screw 21 and is 80 formed with a notch 22 in which is located a rigid pin 23 secured in the side of the carriage and limiting the forward movement of said member.

A link 24 connects the upper end of the 85 pivotal member 20 with one of the upwardly extending arms of the handle frame, consequently the tilting movement of the handle frame on its pivotal support is limited by the stop pin 23.

A set screw 25 is threaded through the 90 rearward end of the lug 8 of the pivotal frame 7 and extends downwardly to engage the top surface of the carriage, said screw being adjustably secured.

A cam plate 26 is slidably mounted upon the carriage 3 being secured by a pair of cap screws 27 inserted in the side and extending through the slots 28 in the cam plate.

The top portion of the cam plate is 100 formed with a sloping surface 29 which is adapted to engage the lower end of the set screw 25. When the cam plate is clear of the set screw 25 the gear pinion 13 rests normally in the rack but when said cam plate is moved forwardly to engage the set screw 25 it lifts the lug so as to move the mandrel pinion out of engagement with the rack.

A link 30 is pivotally connected to the 110 pivotal point of connection of the member

20 with the link 24 so that when the pivotal member 20 is tilted on its pivot the link 30 pulls forwardly on the cam plate forcing the wedge portion thereof beneath the set screw 25 and lifting the mandrel.

This arrangement of mechanism provides that when the handle is grasped by the operator and the carriage is pushed forwardly along the frame the link 24 forms a stop to prevent the handle being tilted too far forward. The forward action operates the link 24 to move the cam plate 26 beneath the set screw 25 so that the lug 18 is lifted upwardly to clear the pinion from engagement 10 with the rack as the carriage is moved forward.

The type from which the impression is to be made upon the collapsible tube is mounted upon a plate 31 arranged beneath the side 20 guides and adapted to be raised or lowered for adjustment and the inking roller being spring held downwardly passes over the type face in the forward movement of the carriage applying ink thereto.

25 In the return movement of the carriage the backward movement of the handle tilts it upon its pivot operating the member 20 and link 30 to move the cam plate clear of the set screw 25 and allow the frame 7 to be 30 sprung downwardly by the pressure of the spring so that the tube carried upon the mandrel will be brought into contact with the face of the inked type.

At the forward end of the machine is arranged an ink distributing plate 32 which is 35 rotatably supported from the frame, the spindle thereof extending downwardly through a sub frame 33. A ratchet wheel 34 is secured to the spindle and a lever 35 is loosely 40 mounted upon the spindle and carries a ratchet dog 36 to engage the wheel 34.

A lever 37 is pivotally supported from a bracket 38 arranged at the forward end of the machine and its opposite end is connected with the ratchet lever 35 by a link 39.

50 A bracket 40 is secured to the underside of the carriage 3 and extends inwardly beneath the lever 37 having a pair of roller contacts 41 adapted to engage the lever. The lever 37 is offset intermediate of its length so that as the carriage is moved forwardly the rollers engage the offset portion and swing the lever upon its pivot, thus operating the ratchet lever with each movement to rotate the inking plate.

55 A machine such as described is of extremely simple construction. There are no delicate adjustments to get out of order and all of the parts are of a simple and strong 60 construction to withstand the strains of operating conditions.

The mandrel may be very readily adjusted in relation to the type by the simple 65 adjustment of the set screw and it will be noted that the natural action of the operator

is utilized to perform the function of lifting the mandrel to clear the printing surface in the forward movement and to bring it into contact therewith in the return movement.

The operator in using this machine places the open ended collapsible tubes upon the mandrel and the forward movement of the hand moves the carriage to bring the inking roller over the ink distributing plate. In 75 the return movement the backward pull brings the tube into contact with the ink surface of the type and at the completion of the back stroke the tube is slipped off the mandrel.

80 What I claim as my invention is:—

1. A tube printing machine, comprising a frame, a carriage reciprocally mounted on said frame, a stationary printing surface, a mandrel adapted to carry the tube into engagement with the printing surface supported on said carriage and engaging the frame in rolling contact, means independent of the mandrel support for reciprocating said carriage on said frame, and means operable by said reciprocating means and arranged upon the carriage for lifting the mandrel clear of the printing surface.

2. A tube printing machine, comprising, a frame, a carriage reciprocally mounted on said frame, a stationary printing surface, a frame pivotally mounted on said carriage, a mandrel mounted on said pivotal frame, means arranged on the main frame for engaging and rotating said mandrel through the reciprocal movement of the carriage, a handle member pivotally supported on the carriage independent of the mandrel frame, and means operatively connected with said handle member adapted on the movement of 105 the carriage in one direction to lift the mandrel clear of the rotating means and the printing surface and upon the movement of the carriage in the opposite direction to allow said mandrel to coöperate with the rotating means.

3. A tube printing machine, comprising, a frame, a carriage reciprocally mounted on said frame, a stationary printing surface, a frame pivotally mounted on said carriage, 115 a mandrel rotatably mounted on said pivotal frame, means for rotating said mandrel through the reciprocal movement of the carriage, a handle member pivotally supported on the carriage, a member pivotally secured 120 at the side of the carriage and having a limited movement, a link connecting said handle with said pivotal member, a cam member adapted to lift the pivotal mandrel frame, and a link connecting said cam member with 125 said pivotal member.

4. A tube printing machine, comprising, a frame, a carriage reciprocally mounted on said frame, a stationary printing surface, a frame pivotally mounted on said carriage, 130

- a mandrel rotatably mounted on said pivotal frame, means for rotating said mandrel through the reciprocal movement of the carriage, a handle member pivotally supported 5 on the carriage, a member pivotally secured at the side of the carriage and having a limited movement, a link connecting said handle with said pivotal member, a plate slidably mounted on the carriage and having an inclined cam surface adapted to engage an extension from the pivotal mandrel frame, and 10 a link connecting said slidable plate with the pivotal member operated by said handle.
5. A tube printing machine, comprising, a frame having parallel longitudinal sides, a carriage reciprocally mounted to slide on
- said frame, a stationary printing surface arranged beneath said carriage, a toothed rack extending longitudinally of the frame, a mandrel frame pivotally supported on the 20 carriage, a mandrel rotatably supported in said mandrel frame and having a toothed pinion adapted to engage said rack, spring means for holding said mandrel frame with the toothed pinion in engagement with the 25 rack, a handle pivotally supported on said carriage separate from the mandrel frame, and means operated by said handle for lifting the pivotal mandrel frame to move the pinion clear of the rack.

WILLIAM FREELAND CORSON.
